APPARATUS FOR REMOVING SURFACE METAL FROM METALLIC BODIES

James H. Bucknam, Cranford, N. J., assignor to
The Linde Air Products Company, a corpora-
tion of Ohio

Application April 26, 1937, Serial No. 139,030

14 Claims. (Cl. 266—23)

This invention relates to apparatus for removing surface defects from metallic bodies, and more particularly to an improved means for projecting gaseous heating and oxidizing jets across a wide path of, or the full width of a surface of a metal body to remove a surface layer of metal therefrom.

Billets, blooms, slabs and similar semi-finished steel shapes are desurfaced to eliminate defects in the surfaces of such shapes and to improve such surfaces for subsequent rolling. Such desurfacing is accomplished by applying a suitable wide oxidizing gas stream obliquely to the heated surface during relative movement of the steel shape and suitable apparatus for applying thereto oxidizing and high temperature heating jets. Heretofore, such apparatus has included a row of blowpipes individually somewhat similar to the oxyacetylene blowpipe used for cutting metals.

Such blowpipes, however, have been independently mounted alongside of each other and carried by a machine which was capable of effecting relative movement between the blowpipes and the work. The surface produced with such an arrangement of blowpipes was not entirely satisfactory, for the channels produced are often too irregular and the ridges left between the paths of each blowpipe may be too prominent. If the individual blowpipes are arranged close enough together in an effort to avoid excessive ridges, the action of the surface of the work on each blowpipe is such that the blowpipes are readily jarred out of adjustment and alignment. The blowpipes are also subject to injury and may be damaged by rough billets which are desurfaced in a steel mill.

A general object of this invention is to provide an improved desurfacing or surface conditioning apparatus for economically and efficiently removing surface metal from blooms, billets, bars, and the like whereby ridges left on the surface may be constantly and uniformly reduced to an inappreciable height and metal is removed to a substantially even depth. More particular objects of this invention are: to provide means for holding the blowpipe nozzles rigidly in alignment with each other so that they cannot be forcibly displaced from their desired relation; to provide means for holding the nozzles so that they may be maintained in closer relation to each other so that the streams produced will merge and produce a practically sheet-like desurfacing stream; to provide means for thoroughly protecting the nozzles from injury by rough billets passing the desurfacing device at a rapid rate; to provide a unitary blowpipe head arranged to be detached quickly as a unit from the desurfacing machine so that it may be replaced by another with very little loss of time;

and to provide a means whereby the desired angular relation of the nozzles to each other and to the surface of the work may be maintained fixed and uniform.

The above and other objects and the novel features of this invention will become apparent from the following description taken with the accompanying drawings, in which:

Fig. 1 is an elevational view partly in section of a desurfacing mechanism according to the present invention;

Fig. 2 is a plan view of the mechanism shown in Fig. 1;

Fig. 3 is a fragmentary horizontal sectional view showing the key means for securing the mounting plate to the carrier in Fig. 1;

Fig. 4 is a fragmentary plan view of the key means shown in Fig. 3;

Fig. 5 is a fragmentary enlarged plan view of the forward end of another form of nozzle shoe according to the invention;

Fig. 6 is a sectional elevation of another form of desurfacing head according to the invention;

Fig. 7 is a plan view of the head shown in Fig. 6; and

Fig. 8 is a bottom view of the head shown in Fig. 6.

Generally the invention comprises a unitary desurfacing head adapted to be carried and operatively moved by a desurfacing machine, such, for example, as the machine described in Patent No. 2,125,174 of H. W. Jones. The desurfacing head comprises a heavy walled box-like shoe for enclosing and protecting one or more blowpipes and having a rear wall adapted for transmitting all shocks received from the billet surface directly to the sturdy supporting mechanism of the desurfacing machine; a forward wall adapted to hold a row of nozzles closely spaced in rigid relation to each other and at the desired angle; a bottom portion or bearing wall adapted to ride on the surface of the billet so that the row of nozzles will always be accurately spaced from the surface being treated; and connecting side walls which complete the shielding and protection for the blowpipes and nozzles. The head is mounted on the desurfacing machine by means permitting rapid removal of the whole unit when desired.

Referring to Fig. 1, the box nozzle shoe is generally indicated at 10 and a blowpipe in operative position in the shoe at 11. The shoe has an open top and comprises a back wall 12, which is secured by four studs 13 to the lower portion of a rectangular mounting plate 14. The shoe has a sturdy bottom wall or sole portion 15, the forward part of which rides in contact with or slides along the surface of the billet and is provided with a layer of hard metal 16 of substantial surface area which resists abrasion when

- subjected to heat, such, for example, as "Stellite" metal. The forward wall of the shoe comprises a removable section 17 disposed at an obtuse angle to the surface 16 and provided with end portions secured to the side walls 18 and 19 of the shoe and a lower edge shaped to semi-enclose the forward portions of the nozzles 20. The upper foremost part of the bottom 15 is correspondingly shaped to semi-enclose the nozzles 20 so that they are secured between the section 17 and the bottom 15 in the desired relation to each other and at the desired acute angle to the surface 16 and thereby to the surface of the work which is indicated at 21.
- 18 It will be seen that the nozzles 20 are completely protected from the effects of heat radiated from the surface of the work except at their orifice ends and that they are substantially fully protected from contact with the work surface 20 and are not subject to serious injury nor to displacement from their desired relative positions by contacts with projections, such as lumps, fins, and scale on the untreated surface of the billets or ingots.
- 25 All shocks and forces caused by such contacts are not transmitted to the desurfacing machine by the nozzles and the gas supply means 11 alone but by the box shoe directly to the desurfacing machine through the shoe supporting mechanism. The supporting mechanism comprises a carrier 22 having a flat forward face against which the plate 14 is held by a mounting stud 23 projecting substantially centrally forward from the face of the carrier through a hole in the plate 14. The stud 23 is provided with a head 24 and a neck 25 of reduced diameter, the head being spaced from the plate a distance sufficient to accommodate a locking key 26. The key 26 is forked having two legs 27 whose forward surfaces 28 are tapered so that when the legs 27 are driven under the head 24 they will wedge between the head and the plate 17 so as to secure the plate 17 tightly to the face of the carrier. The key 26 may be provided with a head projection 29 which may be struck with a hammer to drive it home or to remove it. A projection 30 is secured to the plate 14 below the projection 29 to prevent the key from turning when it is loose.
- The carrier 22 is mounted on and carried by a frame 31 by means that permits the carrier to move relative thereto through a limited distance in the vertical direction or toward and from the surface 21 without changing the angular relation between the nozzles and the work surface. This motion is preferably provided by a parallel linkage connection using four links 32 which are pivoted at their forward ends to bearings 33 and 34 projecting rearwardly from the carrier 22, there being two bearings 33 at the upper corners of the carrier plate and two bearings 34 at the lower corners. The rearward ends of the links 32 are pivoted to corresponding bearings 35 and 36 projecting forward from the frame 31. The upper links 32 are keyed to a horizontal shaft 37 which is journaled in the bearings 35. By turning this shaft, the upper links 32 are rotated and the carrier may be raised thereby.
- Suitable means for turning the shaft is provided by means of a crank arm 38 keyed to the mid portion of the shaft 37 and depending downward therefrom. A second crank arm 39 is disposed on the rear side of the frame 31 opposite the crank 38 being keyed to and depending downwardly from a horizontal transverse shaft 40.
- 75 A connecting link 41 is pivoted at its ends to the

ends of the two crank arms, the link 41 passing through an opening in the frame 31. The shaft 40 is journaled in bearings 42 projecting from the rear face of the frame 31 and is turned by an operating lever 43 whose end is pin keyed to the outwardly projecting portion of shaft 40. The lever 43 is operated to quickly lower or raise the desurfacing head to and from the operating position.

Means is preferably provided to counterbalance the major portion of the weight of the desurfacing head so that the pressure of the shoe riding on the work surface will not be too great and the head will follow the surface with greater sensitivity to variations. To this end, a set of ten compression springs 44 is provided whose upper ends thrust upwardly against a rearwardly projecting bracket portion 45 of the carrier 22 and whose lower ends thrust downwardly against a spring retainer 46. The spring retainer 46 is supported by a threaded vertical stud or pillar 47 which is adjustably secured for vertical adjustment to a forwardly projecting bottom bracket portion 48 of the frame 31. A lock nut 49 is provided on the pillar on the lower side of the bracket 48 to maintain the adjustment setting. The springs are supported and guided by internal rods or tubes 50 which are secured at their lower ends to the retainer 46 and pass slidably through holes provided in the bracket 45.

Stops are provided to limit the degree of motion in both directions. To limit motion upwardly, pins 51 are passed through and secured to the upper end portions of the tubes 50 so as to engage with the bracket 45 when the carrier reaches the extreme upper limit of motion. The stops for the lower limit of motion are provided by the bearing ears 34 whose lower portions engage with the upper surface of the bracket 48.

Referring to Fig. 2, it is seen that the frame 31 has in plan, a channel shaped cross section with forwardly projecting sides 52. These are provided to strengthen and stiffen the frame and to support the bearings 35 and 36 and also the bottom bracket 48. The frame 31 is carried by and secured to the desurfacing machine by pivot or hinge means which allows the frame and all it carries to swing horizontally and transversely of the billet. Such connection is provided by two pivot bearings 53 which project rearwardly from the frame 31 and are secured thereto in vertical alignment close to one side of the frame, preferably the side on which the lever 43 is disposed. The bearings 53 are journaled on and carried by vertical pivots 54 secured to projecting ears 55 carried by a desurfacing machine or supporting mechanism. The desurfacing machine is not shown in the interests of clearness of the drawings since it forms no part of the present invention. Such a machine provides the necessary relative movement of the frame at the proper speed longitudinally of the billet 21 and may also provide a transverse adjustment of the frame with respect to the billet for positioning the shoe 10 over the billet and a vertical adjustment to adjust the vertical position of the shoe according to the height of the billet. Such a machine preferably also provides means for biasing the frame 31 in a direction transversely of the billet about the axis of the pins 54 so that a side guide shoe 56 may be maintained in contact with one side of the billet whereby the shoe 10 will be always maintained in the desired alignment over the billet irrespective of lateral variations thereof. The side guide shoe is secured to the end of 7

a forwardly and downwardly projecting arm 57 of the bracket 48.

The nozzles 20 each have an oxidizing gas passage adapted to produce an oxidizing gas stream having a relatively large volume and a velocity suitable for removing surface metal. They are also preferably provided with an auxiliary passage or passages for projecting heating flames which can be used to heat a portion of surface metal to the ignition temperature for starting a desurfacing cut and for aiding the desurfacing reaction as it progresses over the surface to be removed. The oxygen passages may be supplied with gas from a single supply pipe by a manifold header to which each nozzle is attached. The heating gas passages may likewise be supplied by a single supply passage by suitable manifold connections. However, since it is preferable to supply a mixture of fuel gas with oxygen for the heating flames, a blowpipe means for mixing the gases in the proper proportions may be provided. One such mixing blowpipe may supply all the nozzles or one blowpipe may be provided for one or more groups of nozzles. Likewise more than one oxygen supply passage may be arranged to feed the oxygen passages of the nozzles, but the number of oxygen supply passages and the number of heating gas mixture supplying blowpipes may be different and independent of each other.

In the embodiment shown in Figs. 1 and 2, a separate blowpipe 11 to supply each nozzle 20 is shown. The blowpipes 11 are long, substantially rectangular in cross section, and are narrow in width to permit close side by side spacing. The blowpipes have a lower block 58 to which a nozzle 20 is secured so that its oxidizing gas passage and heating gas passage connect with suitable corresponding passages in the blowpipe. The blowpipes also have an upper block 59 to which flexible supply conduits 60, 61, 62, 63, and 64 are connected as follows: The conduit 60 supplies fuel gas, conduit 61 supplies oxygen for admixture with the fuel gas, conduit 62 supplies the desurfacing oxygen, and the conduits 63 and 64 are cooling water supply and discharge conduits respectively.

All the acetylene supply conduits of the blowpipes may be supplied from a single manifold so that if it is desired to quickly remove the whole desurfacing head from the carrier only one acetylene conduit coupling to the manifold need be separated. Similarly, the conduits for each supply may be manifolded for a like purpose. The lower end of each blowpipe is secured in the shoe 10 in a quick detachable manner by means of a pin 65 projecting downward from a bracket 56 secured to the lower portion of the rear edge of the blowpipe. The pins fit within holes bored in a boss 67 projecting from the bottom 15 of the shoe. The forward edge of each blowpipe has a bracket 68 near its lower end to which is secured a vertically projecting pin 69 and all the pins 69 fit within holes in a horizontal retaining bar 70 having end portions secured to the top of the side walls 18 and 19 by screws 71. The upper portions of the blowpipes are secured to the plate 14 by screws 72 which hold brackets 73 projecting from the rear edge of each blowpipe to a horizontal angle iron 74 secured to the forward face of the plate.

The embodiment shown in Figs. 6 and 7 employs blow-pipes 111 of a smaller and more compact construction, thereby permitting a closer spacing of the blowpipes and consequently a

closer arrangement of the nozzles 20 whereby a more nearly sheetlike desurfacing gas stream may be produced. This form of the invention is more particularly suitable for use with desurfacing machines where the box shoe is applied to sides 5 of the work which are not horizontal. The blowpipes 111 have connections for supply conduits at their upper portions where connection 160 receives fuel gas, 161 receives oxygen for admixture with the fuel gas, 162 receives the 10 desurfacing oxygen, and connections 163 and 164 receive and discharge the cooling water.

The nozzles are mounted in the box shoe in a manner similar to that shown in Fig. 1. The blowpipe 111 being short, however, no direct attachment to the mounting plate is required. The forward portion of the blowpipe has a projecting part 168 which carries the pin 169, the pin being retained in its socket by a set screw 76. The pins 169 pass into holes in bar 170 which 20 is secured to a niche in the upper edge of the side walls 118 and 119 by screws 171. The rear edge of each blowpipe has a bracket 77 secured thereto, the lower end of which bracket carries the downwardly projecting pin 165 that enters the 25 hole 78 in the bottom 115 of the shoe, and the upper end of which is provided with an arm 79 that projects therefrom rearwardly over the top edge of the back wall 112 and is secured thereto by a screw 80. The back wall of the box shoe 30 is provided with suitable holes 86 to admit screws or bolts for securing the box shoe to a mounting plate.

It will be seen that the blowpipes and nozzles are not disposed parallel to each other but are 35 inclined toward each other at angles which increase as the distance outward from the central blowpipe increases. The reason for such arrangement and the result attained thereby is disclosed in Patent No. 2,125,179 of E. A. Doyle. 40 With the present arrangement of the box nozzle shoe, a compact and closer spacing of the tips of the nozzles is obtained. More nozzles of a smaller diameter may be provided in the row so as to produce individual streams which merge 45 and produce overlapping channels in the surface of the work. The ridges between the channels are therefore very small and the depth of surface removal is more uniform which insures that no defects will remain due to insufficient 50 depth of removal. The bottom of the shoe has an external plane surface area which is coated with a layer of hard surfacing material 116, preferably applied as shown in Fig. 8, where the hard surfacing forms a band 81 across the forward edge which joins four strips 82 extending rearwardly from the band 81. This provides adequate resistance to abrasion and is economical in the use of the hard surfacing material.

In certain instances, it is not desirable to have 60 the nozzles 20 toe inward but they may be arranged to be parallel. But where the height of the ridges between channels must be reduced to the minimum and where the slag produced by the desurfacing action is to be washed toward 65 one side only, it is found advantageous to arrange the nozzles at a constant lateral angle with the forward direction or direction in which the desurfacing head is moved in operation. Such an arrangement will be clear by reference to Fig. 5 70 which shows the forward portion of the bottom 215 of a box nozzle shoe. Seven channels 83 are provided for receiving and holding nozzles. Corresponding channels are formed in the nozzle retaining block which is similar to block 17 and 75

is removed to expose the channels 83. The channels 83 are parallel to each other and are at a constant angle to the forward edge of the shoe. A suitable value of this angle for good results has been found to be 86°. Such an angle provides gas streams which sweep laterally a sufficient amount to reduce the height of ridge between the channels a substantial amount.

In operation, to desurface an upper face of a billet, the desurfacing machine is adjusted to move the shoe into position in alignment with, and riding on the top face of the billet, and with the forward corner of the shoe near the end of the billet. The lever 43 is temporarily held in this position and the machine adjusted to move the shoe relatively to the billet in a backward direction and off the end of the surface until the nozzles 20 are opposite the end corner of the billet and preheating flames are projected on the corner until the metal reaches the ignition temperature. When this temperature is reached, which occurs in a short time depending on the initial temperature of the whole billet which may be hot or cold, the oxidizing gas is applied and the machine or the billet is put into longitudinal motion so that the shoe traverses the surface longitudinally at the proper speed to remove a layer of metal of the desired depth. During such movement, the shoe 10 rides or slides on the surface and follows all irregularities, maintaining the nozzles in the desired relation. The lateral guide shoe 56, being urged toward the side of the billet by the transverse bias of the frame 31 causes the shoe 10 to follow variations in the lateral straightness of the billet. Such guide shoe however may also be attached directly to the side wall of the box nozzle shoe. The lever 43 is operated at the end of the pass to raise the shoe 10 for the return stroke. The number of nozzles in use may be varied according to the width of the face to be desurfaced; for example, the desurfacing head shown in Figs. 1 and 2 may desurface an 8 inch wide face with seven nozzles in use, but to desurface a 6 inch wide face, the two outer nozzles are not used. Where very wide surfaces are to be treated in more than one pass, it is preferable to use the form of box shoe shown in Fig. 5, the first pass being made along the right edge of the surface and the second made adjacent the left side of the first pass so that slag is preferably projected over the unfinished surface portion. The side guide 56 is not necessary for such multi-pass desurfacing.

When it is desired to remove the box nozzle shoe assembly from the desurfacing apparatus to quickly replace it with another, for example, when a billet of different width is to be treated or when the nozzles are to be cleaned, the gas and water supply hose couplings are disconnected and the key 26 knocked out, when the mounting plate, box nozzle shoe and blowpipes may be removed as a unit. This rapid change is important in steel mill operations, particularly when the desurfacing device is treating billets passing from one rolling operation to another.

When working on hot billets, the box nozzle shoe is preferably provided with cooling means. This cooling means may be part of the cooling system of the gas supplying device, or may be provided by water sprays which are directed on the portions of the nozzles within the box nozzle shoe. To this end the cooling fluid discharged at 64 from one or more of the blowpipes 11 may be conducted by a tube or tubes 64' which extend downwardly along the blowpipes to a point within

the walls of the shoe directly above the nozzles 20, the lower end of the tubes 64' being directed so as to spray the cooling fluid against the nozzles. By this means, both the box and nozzles are effectively cooled without affecting the heating flames or desurfacing reaction. Packing gaskets 84 are provided around each nozzle to prevent the water from escaping along the nozzle and the water is caused to overflow through a hole 85 in the rear portion of the side wall of the box at 10 the desired level.

While the various features of the apparatus are shown and described in detail to fully disclose certain desirable embodiments of the invention, it will be clear that various changes may be made in such details and some features or parts may be used independently of others, without departing from the principles of the invention.

What is claimed is:

1. Blowpipe apparatus comprising, in combination a blowpipe having a nozzle at one end thereof, and a box-like protecting shoe enclosing at least said end of said blowpipe and substantially completely enclosing said nozzle except the orifice end thereof, said shoe having a bottom wall and side walls, said bottom wall being provided with an external surface portion of substantial area adapted to ride on a work surface, one of said side walls being of substantial thickness and having a passage therethrough, said blowpipe being detachably secured to said shoe in a position such that said nozzle extends from within the shoe into said passage, and the external cross-sectional dimensions of said nozzle being substantially equal to the cross-sectional dimensions of said passage whereby the passage is substantially filled by the nozzle.

2. Blowpipe apparatus comprising, in combination a blowpipe having a nozzle at one end thereof, and a box-like protecting shoe enclosing at least said end of said blowpipe and substantially completely enclosing said nozzle except the orifice end thereof, said shoe having walls forming a chamber adapted to receive a cooling fluid for cooling said shoe, the portion of the blowpipe therein and said nozzle, said nozzle having a portion disposed in a passage through a wall of said shoe, said nozzle being longitudinally slidably in said passage and means for preventing the escape of cooling fluid through said passage and along 50 said nozzle while allowing said nozzle to slide in said passage relatively to said wall.

3. Blowpipe apparatus comprising, in combination, a blowpipe having a nozzle at one end thereof, and a box-like protecting shoe having walls enclosing at least said end of said blowpipe and substantially completely enclosing said nozzle except the orifice end thereof, one wall of said shoe being detachable and having a recess in one edge, and another wall of said shoe having a recess cooperating with the first-named recess to provide an opening to receive a portion of said nozzle and expose the orifice end of the nozzle to discharge gas from the latter outside said shoe.

4. Blowpipe apparatus comprising, in combination, a blowpipe having a nozzle at one end thereof, and a box-like protecting shoe having walls enclosing at least said end of said blowpipe and substantially completely enclosing said nozzle except the orifice end thereof, the bottom wall of said shoe having a recess adjacent its front edge, and the front wall of the shoe being detachable and having a recess at its inner edge cooperating with the recess in the bottom wall to clamp a portion of said nozzle in the opening 75

formed by said cooperating recesses and to expose the orifice end of said nozzle adjacent the outer end of said opening.

5. Surface conditioning apparatus comprising, in combination, nozzle means constructed and arranged to deliver a sheet-like stream of gas obliquely against the surface of a metal body; and a box-like metal shoe for holding said nozzle means at a desired angular relation to said surface and for enclosing substantially the entire nozzle means except the orifice portion thereof from which gas is discharged, said shoe having a row of recesses in one wall, a detachable wall having a corresponding row of recesses, said rows of recesses cooperating to provide a row of openings extending from the inside to the outside of said shoe; and said nozzle means having a plurality of separate nozzles severally extending from the inside of said shoe into said openings, whereby said nozzles are protected and maintained in fixed relation to each other.

6. A nozzle holding and protecting device comprising a box-like metal shoe having walls including a bottom wall, said bottom wall being provided with an external plane surface portion of substantial area adapted to ride on a work surface, at least one of said walls being adapted for securing the shoe to a support, said shoe also having one or more nozzle-receiving openings extending from the inside to the outside thereof, said openings being adjacent the bottom wall of the shoe and having their axes arranged at acute angles with respect to the plane of said surface portion.

35 7. Surface conditioning apparatus comprising, in combination, nozzle means constructed and arranged to deliver a sheet-like stream of gas obliquely against the surface of a metal body; and a box-like shoe for holding said nozzle means at a desired angular relation to said surface and for enclosing substantially the entire nozzle means except the orifice portion thereof from which gas is discharged, said shoe having a wall provided with a plurality of openings extending 40 through said wall and adjacent to the front edge of said shoe, the axes of some or all of said openings being inclined to said front edge; and said nozzle means having a plurality of separate nozzles severally extending from the inside of said shoe into said openings.

8. A nozzle holding and protecting device comprising a box-like metal shoe having a rear wall adapted to be secured to a support, and also having one or more nozzle-receiving openings extending 55 from the inside to the outside of said shoe adjacent to its front corner formed by the front and bottom walls of the shoe.

9. A nozzle holding and protecting device comprising a box-like metal shoe having a rear wall adapted to be secured to a support, a bottom wall adapted to slidably engage the surface of the work, and a front wall removably secured to the shoe, said bottom and front walls having cooperating portions to provide one or more nozzle-receiving openings extending from the inside to the outside of the shoe.

10. Blowpipe apparatus comprising, a carrier adjustable relatively to a surface of the work to be operated upon; a box-like shoe secured to said carrier and having relatively rigid walls including a front wall and a bearing wall adjoining said front wall, said bearing wall having an external portion adjacent said front wall of substantial surface area constructed and arranged to ride on said work surface, and said front wall having an

opening extending therethrough adjacent said external portion of said bearing wall; and a blowpipe detachably secured to said shoe and having a nozzle projecting therefrom into said opening, at least the nozzle end of said blowpipe and said nozzle being entirely enclosed within the walls of said shoe except the orifice end of said nozzle from which gas is discharged.

11. Blowpipe apparatus comprising, a carrier adjustable relatively to a surface of the work to be operated upon; a box-like shoe secured to said carrier, and having relatively rigid walls forming an enclosure including a front wall and a bearing wall adjoining said front wall, said bearing wall having an external portion adjacent said front wall of substantial surface area constructed and arranged to ride on said work surface, and said front wall having an opening extending therethrough adjacent said external portion of said bearing wall; and a blowpipe secured within said shoe and having a nozzle projecting therefrom into said opening, said blowpipe and said nozzle being entirely enclosed within the walls of said shoe except the orifice end of said nozzle from which gas is discharged.

12. Blowpipe apparatus comprising, a carrier adjustable relatively to a surface of the work to be operated upon; a box-like shoe secured to said carrier, and having relatively rigid walls forming an enclosure including a front wall and a bearing wall adjoining said front wall, said bearing wall having an external portion adjacent said front wall constructed and arranged to engage and slide along said work surface, and said front wall having an opening extending therethrough adjacent said bearing wall; and a blowpipe secured within said shoe and having a nozzle projecting therefrom into said opening, said blowpipe and said nozzle being entirely enclosed within the walls of said shoe except the orifice end of said nozzle from which gas is discharged; means for sealing the joint between said nozzle and said front wall to prevent the escape of cooling fluid through said opening; and means for supplying cooling fluid to the enclosure formed by the walls of said shoe.

13. A nozzle holding and protecting device comprising a box-like relatively thick metal shoe having walls including a front wall, at least one of said walls being adapted for securing said shoe to a support, at least one of said walls adjoining said front wall having an external surface portion arranged at an obtuse dihedral angle to said front wall and adapted for riding on the surface of the work, said front wall having at least one nozzle-receiving passage extending from the inside to the outside thereof, the outside end of said passage being adjacent said surface portion of the wall that is arranged for riding on the work.

14. A nozzle holding and protecting device comprising a box-like relatively thick metal shoe having walls including a front wall, at least one of said walls being adapted for securing said shoe to a support, at least one of said walls adjoining said front wall having an external plane surface portion constructed and arranged for riding on the surface of the work, said front wall having at least one nozzle-receiving passage extending from the inside to the outside thereof, the outside end of said passage being adjacent said external surface portion of the wall that is arranged for riding on the work, and the main axis of said passage being inclined at an acute angle to the plane of said external portion.
